UNITED STATES PATENT OFFICE

WILFRID J. ROY, OF EAST ORANGE, NEW JERSEY, ASSIGNOR TO GEMEX COMPANY, A CORPORATION OF NEW JERSEY

BRACELET END CONNECTER

Application filed June 27, 1930. Serial No. 464,134.

This invention relates to a bracelet end connecter for separably connecting the end of the bracelet to a bail or spring pin of a watch, and has for its object to provide a construction which will be held in snug engagement with the bail or cross pin of a watch.

A further object of the invention is the provision of a construction in which the movable member will engage the bail or cross pin of a watch to hold the same in closed position.

With these and other objects and advantageous features in view, the invention consists of a novel arrangement of parts more fully disclosed in the detailed description following, in conjunction with the accompanying drawing, and more particularly set forth in the appended claims.

20 In the drawing:

Fig. 1 is a plan view of a watch showing connecters at each side of the watch each connecting one of the bracelet parts thereto;

Fig. 2 is a central sectional view through 25 the connecter;

Fig. 3 is a section on line 3—3 of Figure 2;

Fig. 4 is a section on line 4—4 of Figure 2;

Fig. 5 is a perspective view of the body part of the connecter;

30 Fig. 6 is a perspective view of the jaw which is pivotally mounted with relation thereto.

It is found desirable in the use of connecters for joining a bracelet strap such as mesh or the like to a watch to provide a detachable connection between the connecter and the bracelet so that the bracelet may be cut off a desired length and attached thereto for shortening the encircling size of the same about the wrist, and it is also found desirable to provide a means for closing the hook or portion engaging the bail of the watch and to engage the bail, spring pin or cross bar portion thereof to assist in holding the jaw in closed position and also to prevent movement which may result in accidental opening of the jaw; and in order to accomplish these results, I have provided a construction in which the body portion is formed with a hook and a jaw is pivoted in the body

having one portion to grip the bracelet and another portion to close the entrance to the hook and at the same time frictionally engage the bail or cross pin of the watch to assist in holding the jaw in closed position; and the following is a detailed description of the present embodiment of my invention, illustrating the preferred means by which these advantageous results may be accomplished.

With reference to the drawing, 10 designates a wrist watch having a bail portion 11 at either side thereof which consists of lugs 12 extending from the watch between which there is mounted a spring pin or cross bar 13 which is removable for receiving certain types of end connections, although it is not necessary to remove the pin for attaching the connecter which is the subject of this invention.

The bracelet parts 14 are joined to the watch by a connecter which consists of a body portion 15 having a front wall 16 extended as at 17 and bent to form a hook of a size and shape to receive the bail or cross pin 13 and swing about the same in a hinging fashion. The edge of the hook is recessed as at 18 intermediate its edge portions 19 and 20. The body 15 is provided with side walls 21 each having an opening 22 to receive trunnions 23 of the jaw 24 to pivotally mount the same in the body. The jaw is provided with a cam portion 25 to swing toward the bracelet part 14 which is positioned between the side walls 21 and engage the same and bind it between the edge of this cam portion 25 and the body 15 of the connecter. Teeth 26 are provided to extend into the bracelet part 14 to increase the holding strength of this cam portion. On the opposite side of the pivotally mounted trunnions 23, a lever portion 27 extends which is provided with a lip 28 of a size to swing through the recess 18 and engage the cross pin 13 of the watch. The lip 28 is curved to conform to the shape of the pin 13 and thus to extend beneath the same slightly so as to grip and prevent accidental swinging of the jaw member 24 to open position. The lever portion 27 at either side of the lip 28 moves into close proximity to the edge 29 of the hook to close the opening thereto and at the same

time snap beneath the detents 30 in the side walls 21 which serve to hold the jaw in closed or working position.

This connector thus snugly fits about the bail or cross pin preventing movement of the same thereon with a consequent diminishing of possibility of accidental opening of the jaw to release the connector from the watch or the bracelet from the connector.

10 While I have described certain construction forms which embody the principles of my invention, it is obvious that other desired changes in arrangement may be made within the spirit and the scope of the invention as 15 defined in the appended claims.

I claim:

1. A bracelet end connector comprising a body member having a hook end to engage the bail or cross pin of a wrist watch, and a 20 jaw member pivotally mounted in said body member and having a portion extending to close the opening at said hook end through which said bail or cross pin passes and also a lip on said jaw member bent at generally 25 right angles to said portion and extending entirely laterally across the jaw and concaved to frictionally engage the bail or cross pin.

2. A bracelet end connector comprising a 30 body member having a hook end to engage the bail or cross pin of a wrist watch, and a jaw member pivotally mounted in said body member and having a portion to close the opening to said hook end through which the 35 bail or cross pin passes and also a lip on said jaw member bent at generally right angles to said portion and extending entirely laterally across the jaw and concaved to fit about and beneath the bail or cross pin and frictionally 40 engage the same.

3. A bracelet end connector comprising a body having a hook end to engage the bail or cross pin of a wrist watch, and a jaw member pivoted in said body having a cam portion 45 to secure the bracelet in said body and a portion extending towards the hook opening and provided with a lip which in turn extends from said portion extending towards the hook at such an angle thereto as to at the same time 50 close the opening to said hook and frictionally engage the bail or cross pin to tightly secure the body thereto.

4. A bracelet end connector comprising a body having an extending hook with a recess 55 in its edge and side walls to receive between them a bracelet end portion, a jaw member pivoted in said side walls provided with a cam portion to bind the bracelet end between it and the body, and a lever arm extending 60 towards the hook and provided with a lip which in turn extends from said arm towards the hook at such an angle thereto as to swing into the said recess to close said hook and frictionally engage a watch bail or cross pin 65 engaged by said hook.

5. A bracelet end connector comprising a body member having an extending hook with a recess in its edge and side walls to receive between them a bracelet end portion, a jaw member pivoted in said side walls provided with a cam portion to bind the bracelet end between it and the body, a lever arm extending 70 towards the hook and provided with a lip which in turn extends from the lever arm at such an angle as to swing into the said recess to close the entrance to said hook and frictionally engage a watch bail or cross pin engaged by said hook, and detents on said side walls over which the jaw must pass in moving to closed or working position.

In testimony whereof I affix my signature.

WILFRED J. ROY.
